UNITED STATES PATENT OFFICE.

GEORGE C. McCONNELL, OF MASSILLON, OHIO, ASSIGNOR TO FIDELITY TIRE & RUBBER CO., A CORPORATION OF ILLINOIS.

DESIGN FOR A TIRE TREAD.

Application filed November 8, 1924. Serial No. 11,321. Term of patent 3½ years.

To all whom it may concern:

Be it known that I, GEORGE C. McCONNELL, a citizen of the United States, residing at Massillon, Stark County, Ohio, have invented a new, original, and ornamental Design for a Tire Tread, of which the following is a specification, reference being had to the accompanying drawing, forming part thereof.

I claim:

The ornamental design for a tire tread or a similar device, as shown.

November 4th, 1924.

GEORGE C. McCONNELL.
